Fig. 6

UNITED STATES PATENT OFFICE.

RAY SCOTT KITCHINGMAN, OF RACINE, WISCONSIN, ASSIGNOR TO HARTMANN TRUNK COMPANY, OF RACINE, WISCONSIN, A CORPORATION OF WISCONSIN.

MACHINE FOR ASSEMBLING GARMENT HANGERS.

Application filed December 8, 1924. Serial No. 754,600.

To all whom it may concern:

Be it known that I, RAY SCOTT KITCHINGMAN, a citizen of the United States, and resident of Racine, in the county of Racine 5 and State of Wisconsin, have invented new and useful Improvements in Machines for Assembling Garment Hangers, of which the following is a description, reference being had to the accompanying drawings, which 10 are a part of this specification.

This invention relates to improvements in machines for assembling garment hangers.

Wardrobe trunks are equipped with hangers for women's garments consisting of a 15 pair of wooden end members connected together by a pair of rods, and it is the principal object of the present invention to provide a machine for quickly and easily assembling garment hangers of this type.

20 A further object of the invention is to provide a device of the class described arranged to receive garment hanger ends and the rods for connecting the same and assemble the hangers by forcing the rods into the ends.

25 A further object of the invention is to provide a manually operated device of the class described arranged with a compound lever- 80 age permitting the application of great force without undue exertion on the part of the operator.

30 A further object of the invention is to provide a machine for assembling garment hangers which is of very simple construction, is easy to operate, is strong and durable, and is well adapted for the purpose 85 described.

With the above and other objects in view the invention consists of the improved machine for assembling garment hangers, and 40 its parts and combinations as set forth in the claims and all equivalents thereof.

In the accompanying drawing in which the same reference characters indicate the same parts in all of the views:

45 Fig. 1 is a front view of the improved garment hanger assembling machine, the garment hanger parts being shown in dotted lines;

50 Fig. 2 is an enlarged fragmentary view of the upper end portion thereof;

Fig. 3 is a side view similar to Fig. 2 and partly in section;

Fig. 4 is a detail sectional view taken on line 4-4 of Fig. 2;

Fig. 5 is a cross-sectional view taken on line 5-5 of Fig. 2;

Fig. 6 is a view similar to Fig. 2 only showing the position of the parts when moved to force the hanger rods into the hanger ends;

Fig. 7 is a cross-sectional view taken on line 7-7 of Fig. 6;

Fig. 8 is an enlarged detail view taken on line 8-8 of Fig. 1;

Fig. 9 is an enlarged vertical sectional view taken on line 9-9 of Fig. 1; and

Fig. 10 is a view of a garment hanger partly assembled, parts being broken away and shown in section.

Referring to the drawing it will appear 70 that the numeral 12 indicates a garment hanger of the type assembled by the improved machine and said hanger comprises a curved end 13 and a straight end 14 connected together by a pair of spaced, elongated metallic rods 15. The ends 13 and 14 are provided with bores 16 and 17 respectively, of slightly less diameter than that of the rods, the rods being forced thereinto.

In the manufacture of the aforementioned 80 type of garment hangers, the ends 13 and 14 are constructed and apertured and the rods 15 are cut. Then, these units are received by the assembling machine and forced together to complete the hangers.

The assembling machine is of elongated 85 form and comprises a base 18 provided with side apertured ears 19 forming means whereby the machine may be secured to a table or support. The base 18 is formed with a longitudinal slot 20 in which an elongated arm 21 is slidably positioned, one end of said arm projecting outwardly from the upper end of the base. The upper end of the base carries a side extension 22 to which a link 23 is pivoted at one end and the other end of said link is pivoted to an actuating lever member 24 which is pivoted at its mid-portion, as at 25, to the upper end portion of the slidable arm 21. The free end portion 90 of the lever is formed for a suitable handle 26 whereby the lever may be gripped and manually actuated and the compound lever- 95 age described permits the application of great force in moving the member 21.

At spaced intervals along the face of the base 18, guide members 27 are secured, said members being constructed as shown in 100 105

Fig. 1 is a front view of the improved garment hanger assembling machine, the garment hanger parts being shown in dotted lines;

Figs. 5 and 7. Each of said guide members is formed with a central transverse slot below the top in which a pair of opposed blocks 28 formed with end recesses 29 are positioned and the other ends of said blocks are recessed to receive coiled springs 30 which are secured therein and to side plates 31, the blocks 28 being laterally movable between the base 18 and top portions 32 of 10 the guide members. Spaced grooves are provided in said members 27 dividing the same into side portions 32 and center portions 33. Eccentrics 34 are revolubly mounted in the lower portions of the blocks 28 and the eccentric portions thereof lie within the base slots 20 between the edges thereof and the edges of the slidable arm 21. It will be observed that the side edges of the slidable arm 21 are formed with a plurality of 20 spaced cam grooves 35 and when the arm 21 is in its normal projecting position the eccentrics engage the wider portions of said cam grooves, the parts being positioned as shown in Fig. 5. When the parts are in 25 this position, the machine can receive garment hanger elements to assemble the same, and the curved end 13 of a hanger is positioned on a flat member 36 and against an overlapping plate 37, both of said members 30 36 and 37 being carried by the slidable arm 21. The plate 37 has a depending spring urged plunger 38 to fit into one of the bores of the hanger end 13 to correctly position the same.

35 The lower end portion of the base 18 has secured thereto a transverse arm 39 and an end plate 40 to position a straight hanger end 14, the outer portion of the arm 39 carrying an adjustable member 41 to adjust 40 the arm to hanger ends of different lengths, the same being shown in detail in Fig. 8. Positioned below the lowermost guide member 27 and secured to the slidable arm 21, is a holding tongue 42 having a raised end portion 43 and when the slidable arm 21 is moved longitudinally the member 42 will be moved therewith to a position wherein the raised portion 43 thereof will overlap the hanger end 14 to hold it in its position.

45 50 With the parts positioned as shown in Figs. 2 and 5, the grooves between the center portions 33 of the members 27 and the side portions 32 form a series of aligned grooves to receive the garment hanger rods 15, the rods dropping onto the lower portions 44 of the blocks 28. Then, to assemble a garment hanger, the lever 24 is actuated to move the slidable arm inwardly, carrying the hanger end 13 with it and forcing 55 the upper end portions of the rods 15 into the hanger end bores 16. During this movement, the eccentrics 34 move over the cam grooves 35 to narrower portions thereof, as 60 shown in Figs. 6 and 7 and the eccentrics, together with the springs 30, will cause the

blocks 28 to move inwardly with respect to each other and the top portions 45 of the blocks will then cover the rod grooves and lock the rods firmly in position. The lower end portions of the rods 15 will be forced 70 into the bores 17 of the hanger end 14 and the ends of the rods will be somewhat flattened by contact with the end plates 37 and 40, to prevent their removal from the hanger ends, thereby completing the assembly of a 75 80 hanger. The plate 36, upon a predetermined movement of the slidable arm 21 is arranged to hit the uppermost guide member 27 to limit the movement of the slidable arm.

85 From the foregoing description it will be seen that the improved machine for assembling garment hangers is of very simple and novel construction, and is well adapted for the purpose set forth.

90 What I claim as my invention is:

1. A garment hanger assembling machine, comprising a stationary member for holding a garment hanger end, a movable member for holding a garment hanger end, means for holding garment hanger rods, and means for moving said movable holding member to move said rods with respect to their holding means to force the end portions of said rods into both of the hanger ends. 95

2. A garment hanger assembling machine, comprising a stationary member for holding a garment hanger end, a movable member for holding a garment hanger end, means for holding garment hanger rods, and manually operated lever means for moving said movable holding member and move said rods with respect to their holding means to force the end portions of said rods into both of the hanger ends. 100

105 3. A garment hanger assembling machine, comprising a stationary member for holding a garment hanger end, a movable member for holding a garment hanger end, means for holding garment hanger rods, means for aligning said hanger ends and said rods and holding them in their correct positions with respect to each other, and means for moving said movable holding member to force the end portions of said rods into both of the hanger ends, said last mentioned means automatically operating the rod aligning and holding means. 110

115 4. A garment hanger assembling machine, comprising an elongated base member having a longitudinal slot, an arm slidably movable in said slot and carrying a plate adjacent one end portion of said base, said plate being adapted to hold a garment hanger end, a member fixed to the other end portion of said base and arranged to hold another garment hanger end, a slotted member secured to the base medially of its ends and adjacent said arm, the slots of said member receiving garment hanger rods, and 120 125 130 135

means for moving said slidable arm whereby the hanger end carried thereby is brought into contact with said rods to force said rods into both of the hanger ends.

5. A garment hanger assembling machine, comprising an elongated base member having a longitudinal slot, an arm slidably movable in said slot and carrying a plate adjacent one end of said base, said plate being adapted to hold a garment hanger end, a member fixed to the other end portion of said base and arranged to hold another garment hanger end, a plurality of spaced guide members secured to the base adjacent said 10 arm and formed with alined slots, the slots of said members slidably receiving garment hanger rods, and means for moving said slidable arm whereby the hanger end carried thereby is brought into contact with 15 said rods to force said rods into both of the hanger ends.

6. A garment hanger assembling machine, comprising an elongated base member having a longitudinal slot, an arm slidably movable in said slot and carrying a plate adjacent one end of said base, said plate being adapted to hold a garment hanger end, a member fixed to the other end portion of the base and arranged to hold another garment 20 hanger end, a plurality of spaced guide members secured to the base member adjacent said arm and formed with alined slots, the slots of said members slidably receiving garment hanger rods, means for 25 moving said slidable arm whereby the hanger end carried thereby is brought into contact with said rods to force said rods into both of the hanger ends, and means automatically operative upon a movement 30 of said slidable arm for locking the rods in 35 said guide slots.

7. A garment hanger assembling machine, comprising an elongated base member having a longitudinal slot, an arm slidably movable in said slot and carrying a plate adjacent one end of said base, said plate being adapted to hold a garment hanger end, a gauge member carried by said plate for correctly positioning the hanger end and holding it to the plate, a member fixed to the other end portion of the base and arranged to hold another garment hanger end, a slotted member fixedly secured to the base medially of its ends and adjacent said arm, the slots of said member receiving garment hanger rods, and means for moving said 40 slidable arm whereby the hanger end carried thereby is brought into contact with said rods to force said rods into both of the hanger ends.

8. A garment hanger assembling machine, comprising an elongated base member having a longitudinal slot, an arm slidably movable in said slot and carrying a plate adjacent one end of the base, said plate being

adapted to hold a garment hanger end, an adjustable member fixed to the other end portion of the base and arranged to hold another garment hanger end, a slotted member fixedly secured to the base medially of 70 its ends and adjacent said arm, the slots of said member slidably receiving garment hanger rods, and means for moving said slidable arm whereby the hanger end carried thereby is brought into contact with 75 said rods to force said rods into both of the hanger ends.

9. A garment hanger assembling machine, comprising an elongated base member having a longitudinal slot, an arm slidably movable in said slot and carrying a plate adjacent one end of the base, said plate being adapted to hold a garment hanger end, an adjustable member fixed to the other end portion of the base and arranged to hold 80 another garment hanger end, a slotted member fixedly secured to the base medially of its ends and adjacent said arm, the slots of said member slidably receiving garment hanger rods, means for moving said 85 slidable arm whereby the hanger end carried thereby is brought into contact with said rods to force said rods into both of the hanger ends, and means for limiting the movement 90 of said slidable arm.

10. A garment hanger assembling machine, comprising an elongated base member having a longitudinal slot, an arm slidably movable in said slot and carrying a plate adjacent one end of said base, said 100 plate being adapted to hold a garment hanger end, a member fixed to the other end portion of said base and arranged to hold another garment hanger end, a slotted member fixedly secured to the base medially of 105 its ends and adjacent said arm, the slots of said member slidably receiving garment hanger rods, and means for moving said slidable arm whereby the hanger end carried thereby is brought into contact with said rods to force said rods into both of the hanger ends, said means including an actuating lever pivoted medially of its ends to the end portion of the slidable arm, and a link connection between the base and the 110 inner end of the actuating lever.

11. A garment hanger assembling machine, comprising an elongated base member having a longitudinal slot, an arm slidably movable in said slot and projecting outwardly therefrom at one end, the side edges of said arm having cam grooves formed therein, a plate fixed to said arm adjacent one end of the base and arranged to hold a garment hanger end, an adjustable member fixed transversely to the other end portion of the base and arranged to hold another garment hanger end, a plurality of spaced guide members secured to the base 120 and over the arm and formed with alined 125 slots, the slots of said members receiving garment hanger rods, and means for moving said slidable arm whereby the hanger end carried thereby is brought into contact with said rods to force said rods into both of the hanger ends.

12. A garment hanger assembling machine, comprising an elongated base member having a longitudinal slot, an arm slidably movable in said slot and carrying a plate adjacent one end of the base, said plate being

slots, said slots receiving garment hanger rods, each of said guide members being provided with a pair of cam actuated slideable plates to close said slots and lock the rods 5 therein upon a movement of the slideable arm, manual means for moving said slideable arm whereby the hanger end carried thereby is brought into contact with said rods to force the end portions of said rods 10 into both of the hanger ends, said means

including an actuating lever pivoted medially of its ends to the projecting end portion of the slideable arm, and a link connection between the base and the inner end of the actuating lever, and stop means for limiting the movement of said slideable arm. 15

In testimony whereof, I affix my signature.

RAY SCOTT KITCHINGMAN.
